STOP MOTION CONTROL

George H. McRae, Thomaston, Ga., assignor of
one-half to J. W. Ansley, Thomaston, Ga.Application July 19, 1938, Serial No. 220,105
Renewed April 25, 1940

2 Claims. (Cl. 139—372)

My invention relates to improvements in looms and more particularly in stop motion controls therefor.

The principal object of my invention is to equip a loom embodying an electric stop motion, with inexpensive quick-acting means for rendering the stop motion effective under control of the filling fork in the event of filling failure.

My invention also comprehends other and subordinate objects all of which together with the exact nature of my improvements will be readily understood when the succeeding description and claims are read with reference to the drawings accompanying and forming part of this specification.

In said drawings:

Figure 1 is a view partly in side elevation and partly in transverse section illustrating the application of my invention.

Figure 2 is a view in top plan of the filling detection fork slides, the filling detection fork, the weft hammer head, and the slide member, together with parts associated with said hammer.

Figure 3 is a view in perspective of the filling detection fork.

Figure 4 is a view in longitudinal section taken on the line 4—4 of Fig. 2 looking in the direction indicated by the arrows and drawn to an enlarged scale.

Figure 5 is a view in transverse section taken on the line 5—5 of Fig. 4.

Figure 6 is a view in perspective of the slide member, and

Figure 7 is a view in perspective of a filling tensioning block presently described in detail.

In the drawings to which reference will now be had by numerals, I have illustrated only those parts of a loom essential to a clear understanding of the invention, to wit, the lay 1 rocked by the shaft 2, the usual filling detection fork slides 3 which are mounted as usual on the breast beam, not shown, the filling detection fork 4 pivoted, as at 5, on the rear end of the slides 3 to swing therebetween, and the filling, or weft, hammer, or vibrator, 6 pivotally mounted on the shaft 7 for oscillation by means of the cam 8, cam shaft 9 and follower 10 with its head 11 in the usual longitudinal slot 12 provided between the detection filling fork slides 3. The filling detection fork 4 has the usual depending tine 13 provided with a lateral rearwardly extending finger 14 intermediate its ends, and a looped end 15 extending forwardly from the upper end of said tine.

The loom parts identified in the foregoing are well understood and need not be described in

detail, it being sufficient to explain that the filling hammer 6 rocks once for every two beats of the lay 1 with its head 11 operating in slot 12 of the filling detection fork slides 3 and the looped end 15 of the filling detection fork 4 is normally held elevated out of the path of movement of said head 11 by the filling thread, not shown, which is stretched across the rear side of the tine 13. In the event of filling failure, as for instance breaking of the filling thread, the tine 13 is released and said end 15 of the filling detection fork 4 drops by gravity down towards slides 3. It is usual in the art to utilize such dropping of the end 15 of the filling detection fork 4 to couple the same to the head 11 of the filling hammer 6 so that upon the forward stroke of said hammer the detection filling fork slides 3 are moved forwardly to operate mechanism for stopping the loom.

The loom with which my invention is concerned is equipped with an electric stop motion of any of the usual types for instance that shown generally in my U. S. Patent No. 2,100,197, dated Nov. 23, 1937, and including a live electrode 16, a grounded electrode 17, and a normally open circuit including a lead 18' from the live electrode 16 and another lead from the electrode 17.

According to my invention, a slide member 19, generally cruciform in cross section, is suitably mounted on the detection filling fork slides 3 intermediate the same, for instance as shown in Fig. 5, in the rear of the head 11 of the filling hammer 6 and pivotally connected at its front end, as at 20, to said head for reciprocation by the latter in said guides. Intermediate its ends the slide member 19 has a vertical central bore 22 therein in which is fitted a bushing 23 of insulation material which in turn has fitted therein a sleeve 24 of conductive material extending slightly below the bushing 23 and member 19 with a set screw 25 threaded diametrically in its lower end. The lead 18 which, as will be understood, extends from one side of the circuit is secured to the underside of the member 19 by a screw 26 and the lead 18' extending from the other side of the circuit is secured in the lower end of the sleeve 24 by set screws 25. The member 19 is of conductive material and has a shoulder 27 extending across the top thereof diametrically of the bushing 23 and sleeve 24, said member being of a width such that the looped end 15 of the filling detection fork 4 will, when said fork drops, span the top of said member forwardly of said shoulder and ride upon said top forwardly of the shoulder thereof.

55

The head 11 of the filling hammer 6 is equipped on one side thereof with a square upright block of rubber 28 adjustably mounted thereon to extend rearwardly thereof by means of a forked bracket 29 to which the block is secured by a bolt 30 and which is adjustably mounted on said head by means of a slot 31 therein and a bolt 32 extending through the slot into said head. The function of the block 28 is to meet the lay 10 in the limit of the forward stroke of the latter and wedge the filling between the same and the lay to tension each filling thread uniformly so that said filling always raises the end 15 of the detection filling fork for a uniform distance clear 15 of the member 19.

In the operation of the described control, as long as no filling failure occurs the detection filling fork 4 is held by the filling in a position such that the end 15 thereof is raised above the slide member 19 and the circuit is open. Until the filling comes in from either side of the loom the looped end 15 rides on the top of said member 19 forwardly of the sleeve 24, that is when the head 11 of hammer 6 is starting on its forward stroke. In the event of filling failure, on the forward stroke of said head 11 the member 19 is moved forward until said end 15 of the filling detection fork 4 engages the upper end of the sleeve 24 in which position it is caught in front of the shoulder 27. At this point the sleeve 24 is bridged by said end 15 to the member 19 and the circuit completed to the lead 18 thus closing said circuit and stopping the loom. As soon as filling is replenished said end 15 is raised 35 thus opening the circuit whereupon the loom resumes operation.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

What I claim is:

1. In a loom having an electrical stop motion including a normally open circuit, a filling hammer arranged to vibrate in opposite directions, means to vibrate said hammer, and a filling detection fork pivotally mounted for gravitational operation under filling failure, means to close said circuit rendered effective under gravitational operation of said fork and operation of said hammer in one direction, and including a slide member reciprocated by said hammer toward and from said fork, a contact mounted in said member and insulated therefrom, and a loop on said fork adapted to descend on said member and bridge said contact thereto. 20

2. In a loom having an electrical stop motion including a normally open circuit, a filling hammer arranged to vibrate in opposite directions, means to vibrate said hammer, and a filling detection fork pivotally mounted for gravitational operation under filling failure, means to close said circuit rendered effective under gravitational operation of said fork and operation of said hammer in one direction, and including a slide member reciprocated by said hammer toward and from said fork, a contact mounted in said member and insulated therefrom, and a loop on said fork adapted to descend on said member and bridge said contact thereto, and a shoulder on top of said member adapted to be engaged by 30 said loop to establish the bridging position of the loop relative to said contact. 25

GEORGE H. MCRAE.
